DESIGN FOR A COMBINED GUN BARREL AND TUBULAR CARTRIDGE MAGAZINE

Harold F. Mossberg, New Haven, Conn., assignor
to O. F. Mossberg & Sons, Inc., New Haven,
Conn., a corporation of Connecticut

Application July 20, 1939, Serial No. 86,095

Term of patent 7 years

To all whom it may concern:

Be it known that I, Harold F. Mossberg, a citizen of the United States, residing in New Haven, in the county of New Haven and State of Connecticut, have invented a new, original, and ornamental Design for a Combined Gun Barrel and Tubular Cartridge Magazine, of which the following is a specification, reference being had to the accompanying drawing, forming a part thereof, in which—

Figure 1 is a side elevational view of a combined gun barrel and tubular cartridge magazine;

Figure 2 is an enlarged side elevational view of the portions shown in solid lines in Fig. 1.

Figure 3 is an enlarged elevational front view; and

Figure 4 is an enlarged bottom view of the front end of the portion shown in solid lines in Fig. 1.

The dominant features of my design are shown in solid black lines in the drawing.

I claim:

The ornamental design for a combined gun barrel and tubular cartridge magazine, substantially as shown and described.

HAROLD F. MOSSBERG.
